GEORGE SKAATS MAYHEW, OF LONDON, ENGLAND, ASSIGNOR TO
GEORGE WILLIAM MELLOR, OF LONDON, ENGLAND.

PROCESS AND APPARATUS FOR PREPARING AND CUTTING VENEERS.

No. 814,062.

Specification of Letters Patent.

Patented March 6, 1906.

Application filed July 11, 1905. Serial No. 269,174.

To all whom it may concern:

Be it known that I, GEORGE SKAATS MAYHEW, a citizen of the United States of America, residing at 2 Basinghall avenue, in the city and county of London, England, have invented a new and useful Improved Process and Apparatus for Preparing and Cutting Veneers, of which the following is a specification.

10 The present application relates to an improved method of lining, shaving, and drying veneers cut in a continuous sheet from a log.

Heretofore in cutting such veneers the log has either been taken when green or if dry or partly dry has been boiled or steamed. The veneers cut off are then passed through the squeezing-rolls to extract the water, then cut in sheets of the size required, and then dried by being piled one on the other with 15 strips of wood between them to allow of the circulation of air to dry them, or passed between hot rollers or on carriers through a hot-air chamber to extract the moisture. In these methods there is a large proportion 20 of waste, as the unsupported veneers are split or broken and become so warped and twisted as to be extremely difficult of application to large surfaces which it is desired to cover.

30 Hitherto the logs which have been faced with a backing previously to shaving off the veneer have not had their faces dried previously to cementing on the paper or like facing, with the result that the faced veneer thus cut warped and twisted and was not satisfactory.

According to the present invention I first dry the face of the log and line it as it rotates with a continuous sheet of tough paper or 40 fabric, which is cemented firmly to the face of the wood, and then shave off the veneer and the paper together, and pass the faced veneer so formed over drying-rollers, and finally wind it into a roll from which it may be applied to the surface to be veneered, either in a continuous sheet or cut into various sizes, as may be required.

45 My invention is more particularly described with reference to the accompanying drawing.

To carry out my invention, I mount a boiled or steamed green log 1 in suitable adjustable bearings 2, shown partly in dotted

lines. The said log 1 is driven at a suitable speed to allow of a veneer being shaved off 55 it by means of an adjustable knife 3. Immediately below said knife I arrange a heated rotating roller 5, mounted on suitable bearings 6, sliding in guides 7 and each controlled by a spring 8, which is adapted to keep said 60 roller always against the face of the log as the latter becomes gradually reduced in diameter. The heat of this roller dries the outermost surface of the log as it revolves. Following this roller at a sufficient distance to 65 allow of a similar adjustment I arrange another roller 10, revolving in an opposite direction to that in which the log revolves and adapted to press a continuous sheet of paper 11, which has been pasted on its inner 70 surface with a quick-setting cementing material adapted to join the sheet of paper to the face of the log as it travels.

The paper may be fed from a roll 16, suitably supported on standards 17, the web of 75 paper 11 passing about guide-rolls to the roll 10, and the paste, cement, or other adhesive may be applied to the web or continuous sheet of paper by a rotating brush 19, running in contact with a feed-roll 20, rotating 80 in the trough 21, containing the paste or other adhesive material.

As will be easily understood from the drawing, the roller 10 presses this sheet of paper firmly against the face of the log. Following 85 this roller 10 and similarly adjusted I arrange other heated pressure-rollers 12 and 13, mounted in guides 7 and controlled by springs 8, and which rollers press and dry the cemented sheet upon the face of the log, so that 90 by the time the faced surface of the log reaches the point where the blade 3 shaves off the veneer and the paper cemented on it from the face of the log the paper and veneer are firmly cemented together. The faced 95 veneer thus shaved off is passed over drying-rollers 14, which extract the remainder of the moisture left in the veneer. The sheet of paper-lined veneer is then rolled on a reel 15, from which it may afterward be unwound in 100 a continuous sheet or cut into various sizes, as may be desired.

The hot roller 5 dries the outer surface of the log, but not to a depth as great as the thickness of the veneer being cut, and to this 105 dried outer surface the web of cemented paper

11 will adhere better than it would if the surface were wet, and this partial drying of the veneer stock serves to lessen the tendency of the veneer to warp when the paper is applied 5 thereto.

By this method of cutting and facing veneer all waste by splitting or buckling is avoided and the veneers may be applied to the surface desired, which can be done more 10 readily than such veneers as are cut without a paper backing or with a paper backing which has been applied to the face of the log before said face has been dried.

What I claim is—

15 1. In a machine for the manufacture of faced veneers in continuous sheets, the combination with means for supporting a revolving log, of a rotating heated roller adapted to dry the face of the log, means for applying an

20 adhesive to a continuous sheet or web of lining material, as paper or the like, means for pressing the continuous sheet of cemented paper or the like on the dried face of the log as the latter rotates, means for pressing and 25 drying the cemented sheet of paper or the like upon the face of the log, and means for shaving off a paper-faced veneer from the log.

2. In a machine for the manufacture of faced veneers in continuous sheets, the combination with means for supporting a revolving log, of a rotating heated roller adapted to dry the face of the log, means for applying an adhesive to a continuous sheet or web of lining material, as paper or the like, a facing- 30 roller adapted to press the continuous sheet of cemented paper or the like on the dried face of the log as the latter rotates, means for pressing and drying the cemented sheet of paper or the like upon the face of the log, and means for 35 shaving off a paper-faced veneer from the log.

3. In a machine for the manufacture of faced veneers in continuous sheets, the combination with means for supporting a revolving log, of a rotating heated roller adapted to dry the face of the log, means for applying an adhesive to a continuous sheet or web of lining material, as paper or the like, a facing- 40 roller adapted to press a continuous sheet of cemented paper or the like on the dried face of the log as the latter rotates, means for pressing and 45 drying the cemented sheet of paper or the like upon the face of the log, and means for shaving off a paper-faced veneer from the log.

45 4. In a machine for the manufacture of faced veneers in continuous sheets, the combination with means for supporting a revolving log, of a rotating heated roller adapted to dry the face of the log, means for applying an adhesive to a continuous sheet or web of lining material, as paper or the like, a facing- 50 roller adapted to press and dry the cemented sheet of paper or the like upon the face of the log,

and means for shaving off a paper-faced veneer from the log.

55

4. In a machine for the manufacture of faced veneers in continuous sheets, the combination with means for supporting a revolving log, means for applying an adhesive to a web or continuous sheet of lining or facing 60 material, as paper or the like, of a rotating heated roller adapted to dry the face of the log, a facing-roller adapted to press the continuous sheet of cemented paper or the like on the dried face of the log as the latter rotates, heated rollers adapted to press and dry the cemented sheet of paper or the like upon the face of the log, and an adjustable knife 65 adapted to shave off a paper-faced veneer from the log.

70

5. In a machine for the manufacture of faced veneers in continuous sheets, the combination with means for supporting a revolving log, of a rotating automatically-adjustable heated roller adapted to dry the face of the 75 log, means for applying an adhesive to a continuous sheet or web of paper or the like, an automatically-adjustable facing-roller adapted to press the continuous sheet of cemented paper or the like on the dried face of the log 80 as the latter rotates, automatically-adjustable heated rollers adapted to press and dry the cemented sheet of paper or the like upon the face of the log, an adjustable knife adapted to shave off a paper-faced veneer from the 85 log, and a series of drying-rollers adapted to extract the remainder of moisture from the veneer as it passes over them from the log to the reel.

90

6. A process of manufacturing veneers 95 faced with paper or the like cut in a continuous sheet from a rotating boiled, steamed or green log, consisting in first drying the face of the log as it rotates, then lining said dried face with a continuous sheet of tough paper 95 or the like, then again drying the faced surface, and finally shaving off the dried, faced surface in the form of a thin continuous strip or veneer, substantially as described.

In witness whereof I have signed my name 100 to this specification in the presence of two subscribing witnesses.
